EASEL SUPPORT

Howell N. Tyson, Jr., Evanston, Ill.

Application March 31, 1939, Serial No. 265,068

8 Claims. (Cl. 248—349)

My invention relates to easel supports and more particularly to an easel support which is adjustable to support an easel in various positions.

Although the easel support disclosed herein is illustrated and described in a particular adaptation to the supporting of an easel in connection with photographic enlarging equipment, it will be apparent that there are many other adaptations therefor. As an example, the support **10** might well be used for supporting an easel which holds the work to be copied by a photostating machine. In fact, the structure is well adapted for uses in which a supported device is to be angularly and linearly movable to a predetermined **15** position in a single plane and then locked in the adjusted position by the operation of a single locking element.

It is an object of my invention to provide a support for an easel, or the like, which is adjustable angularly and linearly in a given plane. **20**

Another object of my invention is to provide an adjustable support for an easel, or the like, which may easily and quickly be locked in an adjusted position.

25 Another object of my invention is to provide a support for an easel, or the like, which may be anchored to a base and to which the easel, or the like, is normally attached in one of a plurality of angular positions; the support being adapted **30** to permit adjustment of the easel, or the like, to intermediate angular positions and linearly with respect to the base.

Another object of my invention is to provide an adjustable support for easels, and the like, **35** which may be locked in a particular position by movement of a single locking element and which is entirely made up of parts that are easily and cheaply manufactured and assembled.

Other objects and advantages of my invention **40** will be apparent from the following description and references to the drawings wherein a preferred embodiment of my invention is clearly described and illustrated.

In the drawings: **45**
Fig. 1 is a perspective view of one form of apparatus with which a preferred embodiment of my invention is adapted to be utilized;

Fig. 2 is a fragmentary top view of a preferred embodiment of my invention with parts cut away **50** to emphasize the structural details of the invention;

Figs. 3 and 4 are fragmentary sectional views taken substantially on lines 3—3 and 4—4, respectively, of Fig. 2 and in the direction of the **55** arrows;

Figs. 5 and 6 are fragmentary plan views of the apparatus shown in Fig. 2 which emphasize certain features of my invention; and

Figs. 7 and 8 are plan views of certain parts of the apparatus shown in Figs. 2, 5 and 6. **5**

With particular reference to the drawings, Fig. 1 illustrates one type of equipment with which my invention may be utilized. This equipment comprises photographic enlarging apparatus **10** having a baseboard **11** to which an upright bar **10** or standard **12** is secured by a flanged member **13**. Picture projecting apparatus comprising a lamp housing **14**, a film carrier **15** and a focusing mechanism **16** are mounted on a bracket **17** which is vertically slidable on the standard **12** to vary **15** the size of the projected image. The bracket **17** is secured in an adjusted position by a thumb screw **18**. An easel **20** comprising a board **21**, side masking strips **22** and **23** and adjustable masking strips **24** and **25** is utilized to hold the **20** sensitized paper upon which the image is projected. The masking strips **22**, **23**, **24** and **25** when adjusted to the proper size for a particular projected image, hold the sensitized paper flat and mask the edges thereof to provide a border. **25**

In order that a desired portion of a projected image may be composed to suit the taste and desires of the operator and to project it at a desired angle upon a sensitized paper of a given size, the easel **20** is preferably movable to various adjusted positions with respect to the base **11**. It is also desirable for making duplicate prints and for holding the easel steady that it may be locked in adjusted position with respect to the base **11**. It is for the accomplishment of **30** the adjustment and locking of the position of the easel **20** that my invention is particularly adapted. It is understood, of course, that although the easel herein represented is illustrated in connection with photographic apparatus, it is also **35** as well adapted to holding a paper, or the like, which is to be copied on a photostat machine. There may also be other similar adaptations. **40**

Referring now more particularly to Figs. 2 to 8, inclusive, a base plate **28** is secured to the **45** base **11** by screws **29** and **30** or other suitable fastening means. Arms **31** and **32** are rotatably secured to the base plate **28** by a suitable stud **33** having a head portion **34**; the stud being secured to the base plate **28** by riveting at **35**. The arms **50** **31** and **32** are preferably spaced by a washer **36** that is mounted on the stud **33** between the arms **31** and **32**. The stud **33** thus provides a common center of movement for the arms **31** and **32**. The arms **31** and **32** have enlarged and substantially **55**

fan-shaped end portions 37 and 38, respectively, on one side of the stud 33, which end portions preferably have arcuate slots 40 and 41, respectively, therein. The arcuate slots 40 and 41 preferably have substantially the same radius and, as in the present instance, when both arms are rotatably supported by a common stud 33, the slots are concentric with respect to the center of rotation of the arms or the stud 33. The slots in the respective end portions are necessarily concentric with respect to the axis of rotary movement of the arms.

An arm 43 has one end rotatably secured to the end of the arm 31 opposite the widened end portion 37 by a rivet or other suitable means 44. The other end of the arm 43 is rotatably secured by a rivet or other suitable means 45 to an easel support which preferably comprises a spider 46. To effect the proper spacing between the arm 43 and the spider 46, a washer or bushing 47 is mounted on the rivet 45 between the arm 43 and the spider 46. To stabilize the easel support or spider 46, the heads of the rivets 44 and 45 are preferably enlarged and of the proper size to engage the base 11 and to provide feet. A preferred form for the rivet head is indicated at 49 in Fig. 4 on the rivet 45.

An arm 50 has one end rotatably secured to the end of the arm 32 opposite the enlarged portion 38 by a rivet or other suitable means 51. The other end of the arm 50 is rotatably secured to the spider 46 by a rivet 52 or other suitable means. The rivet 52 has a head 53 that is slideable on the base 11 to provide a foot for supporting and stabilizing the spider 46. A washer or bushing 54 of the proper thickness is mounted on the rivet 52 to properly space the arm 50 from the spider 46. The rivets 45 and 52 which secure the arms 43 and 50 to the spider 46 are preferably spaced apart to provide greater freedom and latitude of movement of the spider 46.

An auxiliary or locking arm 55 is rotatably secured to the arm 50 by a rivet or suitable fastening means 56; the rivet or fastening means 56 being located intermediate the ends of the arm 50. The auxiliary or locking arm 55 has a slot 57 therein that extends angularly across the slots 40 and 41 in the end portions 37 and 38 of the arms 31 and 32. A stud 59 preferably has a square end portion 60 that extends through the base plate 28 and is riveted to that base plate at 61. This stud 59 extends through the slots 40, 41 and 57 and has a locking handle 62 threaded thereon. Washers such as 63 and 64 are preferably mounted on the stud 59 between the auxiliary or locking arm 55 and the arm 32 and between the arms 32 and 31.

An easel support plate 66 is secured to the bottom of the easel 20 by screws such as 67 and 68. This easel support plate 66 is preferably centrally located on the bottom of the easel 20. A stud 69 is secured to the center of the easel support plate by riveting at 70 and projects from the easel support plate and away from the easel. This stud fits into a bearing 71 that is secured to the spider 46. The easel support plate has recesses or notches such as 72, 73, 74 and 75 in the periphery thereof that are spaced at predetermined and angular positions. In the preferred embodiment illustrated, the recesses 72, 73, 74 and 75 are substantially ninety degrees (90°) apart. These recesses 72, 73, 74 and 75 fit and are engaged by an angularly disposed tongue 77 on the spider 46 to determine the angular position of the easel support plate 66

and the easel 20 with respect to the spider 46. The stud 69 is preferably longer than the tongue 77 so that the easel 20 may be raised to a position such as that indicated at 20a in Fig. 4 by dot-dash lines to disengage the tongue 77 from one of the recesses 72, 73, 74 or 75 without disengaging the stud 69 from the bearing 71. In this raised position, the easel 20 may be rotated with respect to the spider 46 until the desired angular position of the easel is obtained and until the tongue 77 engages another of the recesses 72, 73, 74 or 75. This feature gives what might be termed a rough adjustment of the angular position of the easel 20 with respect to the base 11.

With the locking handle 62 loosened by movement to a position such as that indicated at 62a in Fig. 2, the arms 31, 32, 43 and 50 and the spider 46 are free to move to permit angular and linear adjustment of the position of the easel 20 with respect to the base 11. Various adjusted positions of the easel 20 are indicated in Figs. 2, 5 and 6 and by the dot and dash lines at 20b in Fig. 5. As illustrated, the easel is practically universally movable in a given plane with respect to the base 11 and may also be moved angularly for fine angular adjustment, as indicated by the dot and dash lines at 20a in Fig. 6. After the proper adjusted position of the easel 20 is attained, the easel is locked in that position by moving the single locking handle 62 to tighten that handle with respect to the end portions 37 and 38 and the locking arm 55. The positions of the arms 31 and 32 are maintained by the clamping of the end portions 37 and 38 between the handle 62 and the base plate 28. The clamping of the auxiliary or locking arm 55 determines the positions of the arms 50 and 43 and the spider 46 and prevents movement thereof.

It is thought that the invention and many of its attendant advantages will be understood from the foregoing description, and it will be apparent that various changes may be made in the form, construction, and arrangement of the parts without departing from the spirit and scope of the invention or sacrificing all of its material advantages, the form hereinbefore described being merely a preferred embodiment thereof.

What I claim as new and desire to cover by Letters Patent is:

1. An adjustable support for an easel or the like comprising, in combination, a base plate, a pair of arms rotatably secured to the base plate for rotary movement about a common axis, said arms having overlapping enlarged end portions, said end portions having aligned arcuate slots therein which are concentric with the axis of rotary movement of the arms, a spider having angularly disposed arms, one of the arms of said spider having an angularly projecting lug at the end thereof, a second pair of arms each having one end rotatably secured to one of the ends of the first mentioned pair of arms opposite the enlarged end portions thereof, said second pair of arms also having their other ends rotatably connected to the spider at spaced positions, an additional arm having one end rotatably connected to one of the said second pair of arms intermediate the ends thereof, said additional arm having a slot therein which crosses said arcuate slots, manually operable screw means extending through said slots for clamping the arms in fixed positions with respect to base plate, and a plate having slots therein adapted to engage said lug in any one of a plurality of different angular positions.

2. An adjustable support for an easel or the like comprising, in combination, a base plate, a pair of angularly disposed arms having widened end portions, one of which end portions over- laps the other, a single means rotatably securing the said arms to the base plate intermediate the ends thereof, said widened end portions having arcuate slots therein of substantially the same radius and substantially concentric with respect to said means, a spider, a second pair of arms, means rotatably securing each of the second pair of arms to one of the first mentioned pair of arms and to the spider, a locking arm rotatably secured to one of the second pair of arms and having a substantially linear slot therein extending across the arcuate slots, means extending through said slots for clamping the arms in a fixed position, and a plate supported by said spider. 10
- 20 3. An adjustable support for an easel or the like comprising, in combination, a base plate, a first pair of arms, means rotatably securing the arms to the base plate for rotary movement in parallel planes, each of said arms including an end portion having a surface curved concentrically with respect to said means for rotatably securing it to the base plate, a second pair of arms each rotatably secured at one end to one of the first pair of arms, means rotatably secured to and connecting the other ends of the second pair of arms, a locking arm rotatably connected to one of the second pair of arms intermediate the ends thereof, said locking arm extending across the curved surfaces of said end portions, and a single clamping means for securing the locking arm and end portions in an adjusted position with respect to the base plate to lock the arms. 25
- 30 4. An adjustable support for an easel or the like comprising, in combination, a main support, a first pair of arms, means rotatably securing the arms to the main support, a second pair of arms each rotatably secured at one end to one of the arms of said first pair, means rotatably secured at spaced positions thereon to the other ends of the second pair of arms, a locking arm connected to one of the arms, and a single means for locking all of the arms and the last mentioned means in fixed adjusted positions. 35
- 40 5. An adjustable support for an easel or the like comprising, in combination, a main support, a plurality of arms and a spider rotatably connected together so that the longitudinal axes of the arms and one axis of the spider together form a closed polygon and the arms and the spider are relatively angularly movable to adjust the position of the spider linearly and angularly with respect to the main support, means rotatably securing one of the arms to the main support, and means for locking the spider in a fixed adjusted position with respect to the main support. 45
- 50 6. An adjustable support for an easel or the like comprising, in combination, a main support, five members rotatably connected together to form a closed polygon the shape of which polygon is varied by application of force to one of said members, means rotatably connecting two of the members to the main support, one of the other of said members providing an easel support, and means including extensions on the members that are rotatably connected to the base and an arm rotatably connected to one of the members for locking the member which provides the easel support in a fixed position with respect to the main support. 55
7. An adjustable support for an easel or the like comprising, in combination, a main support, a plurality of members rotatably connected together so that their longitudinal axes form a closed polygon, means connecting the members to the main support so that one of the members is rotatably adjustable and movable in any direction within predetermined limits in a given plane with respect to the main support, the said adjustable member providing an easel support and means including an auxiliary arm for locking the easel support member in a fixed position. 60
8. An adjustable support for an easel or the like comprising, in combination, a main support; an auxiliary easel support member; means comprising a plurality of relatively movable elements connecting the easel support member to the main support; said easel support member, relatively movable elements and main support being pivotally connected so that the easel support is rotatably adjustable and movable in any direction within predetermined limits in a given plane; and a single manually operable locking member for locking the easel support member in a position to which it is adjusted. 65

HOWELL N. TYSON, JR.
